CLAIM

The ornamental design for a pool float lounger, as shown and described.

DESCRIPTION

FIG. 1 is a perspective view of the pool float lounger showing my new design;
FIG. 2 is a another perspective view of the pool float lounger showing my new design;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and
FIG. 8 is a bottom plan view thereof; and,
FIG. 9 is a partial enlarged view of portion 9 in FIG. 1. The broken line showing of the pool float is for the purpose of illustrating portions of the article that forms no part of the claimed design. The dot-dash lines that demarcate claimed areas in FIGS. 1 & 9 have been included to show enlargement for clarity. The lines themselves do not form part of the claimed design.

1 Claim, 9 Drawing Sheets
